[57] CLAIM

The ornamental design for a lid for waste basket, as shown and described.

DESCRIPTION

FIG. 1 is a top and front perspective view of a lid for waste basket showing my new design;

FIG. 2 is a top and front perspective view thereof showing the lid on a waste receptacle. The broken lines are for illustrative purposes only;

FIG. 3 is a front elevational view thereof.

FIG. 4 is a rear elevational view thereof.

FIG. 5 is a top plan view thereof.

FIG. 6 is a bottom plan view thereof.

FIG. 7 is a side elevational view thereof; the opposite side being a mirror image.

FIG. 8 is a cross sectional view thereof taken along the line 8 FIG. 5.

FIG. 2

FIG. 3

FIG. 4

FIG. 6

FIG. 7

FIG. 8
